Geo. Himmel ATTORNEY.

Patented Dec. 26, 1922.

UNITED STATES PATENT OFFICE.

WILLIAM V. MALONE, OF JOPLIN, MISSOURI.

GAS HEATING BURNER.

Application filed November 22, 1921. Serial No. 516,998.

To all whom it may concern:

Be it known that I, WILLIAM V. MALONE, a citizen of the United States, residing at Joplin, in the county of Jasper and State 5 of Missouri, have invented certain new and useful Improvements in Gas Heating Burners, of which the following is a specification.

This invention relates to heating devices 10 wherein inflammable gas is utilized as the heating medium and has for one of its objects to provide a device of this character wherein the parts are so arranged that the gas is commingled with the proper proportion 15 of air to produce an intense heat where the flow of the commingled air and gas are interrupted, or checked.

Another object of the invention is to provide a device of this character including a holder for a crucible, the holder being cylindrical in outline and open at the ends, and a burner located at a sufficient distance 20 below the holder to provide for a proper commingling of air and gas to produce an intense heat within the holder, the holder thus providing a combined mixing and 25 combustion chamber.

With these and other objects in view, the invention consists in certain novel features of construction as hereinafter shown and 30 described and then specifically pointed out in the claims, and in the drawings illustrative of the preferred embodiment of the invention;

The figure represents a vertical sectional 35 elevation of the improved device.

The improved device comprises a support 40 10 of suitable form and including a cylindrical holder 11 open at the top and bottom and adapted to sustain a melting pot or crucible 12 for containing the fusible metal or compound or material, such as Babbet metal, type metal, lead or tin compounds and the like, which are fusible at comparatively low temperatures. The crucible 45 serves also as a closure to the upper end of the cylindrical holder.

Disposed below the holder 11 and spaced therefrom is a gas burner 12 of suitable con-

struction, the burner being disposed in vertical alinement with the vertical axis of the 50 holder 11, and at a sufficient distance from the holder to enable the proper proportion of air to be commingled with the gas in its passage through the open and unobstructed space between the burner and holder to 60 produce an intense heat within the holder, which thus becomes a combined mixing and combustion chamber. The obstruction produced by the crucible suddenly checks the upward flow of the combined gas and air 65 and causes them to burn with accelerated intensity, and thus materially decreases the length of time required to fuse the contents of the crucible.

The burner must be located from six to 70 fourteen inches below the lower line of the holder, and this distance is the essential feature of the improved device.

The holder 11 must necessarily be of refractory material to withstand the intense 75 heat to which it will be subjected.

The preferred embodiment of the invention is disclosed in the drawings and set forth in the specification, but it will be understood that modifications within the scope 80 of the claimed invention may be made in the construction without departing from the principle of the invention or sacrificing any of its advantages.

Having thus described the invention, 85 what is claimed as new is:—

A heating apparatus of the class described comprising a holder having vertical walls and obstructed at the upper end, a feeder for combustible gas located below said 90 holder and in alinement therewith, the space between the holder and feeder being unobstructed and the distance sufficient to insure the requisite air being absorbed by the gas during the passage of the gas to 95 produce an intense heat within the holder and against the obstruction therein.

In testimony whereof, I affix my signature hereto.

WILLIAM V. MALONE.
